ADJUSTABLE CLOTHES HANGER

Thomas H. Hannon, Waterbury, Conn.

Application May 17, 1951, Serial No. 226,779

6 Claims. (Cl. 223—89)

1

This invention relates to clothes hangers and more particularly to an adjustable clothes hanger for supporting garments of various sizes such as suit coats, overcoats and shirts.

One object of the invention is to provide a clothes hanger of the above nature having extensible shoulder portions which may be adjusted to support properly garments of various sizes.

Another object is to provide a clothes hanger of the character described having means for locking it in any desired adjusted condition.

A further object is to provide a device of the above nature which will be simple in construction, inexpensive to manufacture, easy to manipulate, compact, ornamental in appearance, and very efficient and durable in use.

With these and other objects in view there has been illustrated on the accompanying drawing one form in which the invention may conveniently be embodied in practice.

In the drawing:

Fig. 1 represents a front view of the improved clothes hanger showing the extensible shoulder portions in retracted position.

Fig. 2 is a view similar to that shown in Fig. 1, but showing the shoulder portions in extended position.

Fig. 3 is a horizontal cross-sectional view, taken along the broken line 3—3 of Fig. 1, looking downwardly.

Fig. 4 is a vertical cross-sectional view taken along the line 4—4 of Fig. 2, looking in the direction of the arrows.

Referring now to the drawing in which like reference numerals denote corresponding parts throughout the several views, the numeral 10 indicates generally the improved adjustable clothes hanger embodying the invention, the same comprising a flat hanger body 11 and a pair of flat complementary left and right hand extensible shoulder members 12, 13, respectively, slidably disposed against said hanger body. The body and shoulder members are preferably made of plastic, or they may be constructed from a strong light weight material such as plywood or aluminum.

The hanger body 11 comprises an upper hook 14 integrally formed with a pair of opposed outwardly and downwardly curved shoulder portions 15, 16, interconnected by a central horizontal guide portion 17 and a lower horizontal brace portion 18.

The shoulder members 12, 13 have curved outer edges 19, 20, respectively, conforming generally in shape to the shoulder portions 15, 16

2

of the hanger body 11, as best seen in Fig. 1.

In order that the slidable shoulder members may be adjustably fixed against the hanger body 11, the guide portion 17 thereof is provided with an aligned pair of upper opposed horizontal slots 21, 22, having a series of semi-circular serrated portions 21a, 22a, along their upper edges, respectively, and an aligned pair of lower opposed horizontal slots 23, 24, having a series of semi-circular serrated portions 23a, 24a along their lower edges respectively, the lower slots being outwardly off-set with respect to the upper slots. The shoulder members 12, 13 are provided with integral outstanding headed studs 25, 26, 27, 28 respectively, in alignment with their respective upper and lower slots and slidably therein.

The slots 21, 22, 23, 24 are provided at their outer ends respectively, with upwardly-extending circular openings 25a, 26a, 27a, 28a, slightly greater in diameter than the heads of the headed studs 25, 26, 27, 28, whereby the shoulder members 12, 13 may be slidably assembled to the hanger body 11.

In order that garments having thin shoulder straps may also be hung on the improved clothes hanger, the brace portion 18 at each end is provided with an upwardly and inwardly extending strap holder slot 33.

30

Operation

Fig. 1 illustrates the improved clothes hanger showing the extensible shoulder members in retracted position for hanging garments of narrow shoulder width. In order to use the improved adjustable hanger for garments of greater shoulder width, it is merely necessary to pull out the shoulder members 12, 13 to the required width. The weight of the garment hung upon the hanger will impart a downward force upon the outer ends of the shoulder members 12, 13, to move the studs 25, 26, 27, 28, into locking engagement with their respective serrated portions 21a, 22a, 23a, 24a.

While there has been disclosed in this specification one form in which the invention may readily be embodied, it is to be understood that this form is shown for the purpose of illustration only, and that the invention is not to be limited to the specific disclosure but may be modified and embodied in various other forms without departing from its spirit. In short the invention includes all the modifications and embodiments coming within the scope of the following claims.

Having thus fully described the invention, what

is claimed as new, and for which it is desired to secure Letters Patent, is :

1. In an adjustable clothes hanger, the combination comprising a flat hanger body having a central upwardly extending hook portion, outwardly and downwardly opposed shoulder portions integral with the lower end of said hook, and a central guide portion integrally formed with and horizontally disposed between said opposed shoulder portions, said guide portion being provided with an upper pair of horizontal aligned slots and a lower pair of horizontal aligned slots; slideable complementary right and left flat shoulder members, each having an outer edge conforming generally in shape with said outwardly and downwardly extending shoulder portions, and means passing through said slots to slidably retain said shoulder members against said opposite shoulder portions of said hanger body, whereby said shoulder members may be extended to accommodate 20 clothing of different sizes.

2. The invention as defined in claim 1 wherein said retaining means comprises headed studs extending outwardly of said shoulder members and

slidably disposed within said slots, said upper slots each being provided with a series of semi-circular serrated cut-out portions along their upper edge, said lower slots each being provided with a series of semi-circular serrated cut-outs along their lower edges.

3. The invention as defined in claim 1 wherein said lower slots are outwardly offset with respect to said upper slots.

4. The invention as defined in claim 1 including an integral horizontal brace connecting the lower ends of said opposed shoulder portions.

5. The invention as defined in claim 4 wherein said brace is provided at each end with auxiliary means for supporting other garments.

6. The invention as defined in claim 2 wherein each of said slots terminates at its outer end in an upwardly extending circular opening of greater diameter than the heads of said headed studs, whereby the shoulder members may readily be assembled with the hanger body.
